UNITED STATES PATENT OFFICE.

EDWARD A. FIELD AND EDWARD A. FIELD, JR., OF OAK PARK, ILLINOIS.

INTERNAL-COMBUSTION ENGINE.

1,372,343.

Specification of Letters Patent. Patented Mar. 22, 1921.

Application filed June 21, 1920. Serial No. 390,611.

To all whom it may concern:

Be it known that we, EDWARD A. FIELD and EDWARD A. FIELD, Jr., citizens of the United States, residing at Oak Park, county 5 of Cook, State of Illinois, have invented certain new and useful Improvements in Internal-Combustion Engines, of which the following is a specification.

This invention relates to improvements in 10 internal combustion engines.

Our improvements relate particularly to internal combustion engines of the high compression type.

The main objects of this invention are: 15 First, to provide an improved internal combustion engine of the high compression type which is of high efficiency.

Second, to provide in an internal combustion engine of the high compression type 20 an improved charging or fuel feeding means.

Third, to provide an improved internal combustion engine in which the quantity of fuel delivered is controlled by an air control means.

25 Further objects and objects relating to structural details will definitely appear from the detailed description to follow.

We accomplish the objects of our invention by the devices and means described in 30 the following specification. The invention is clearly defined and pointed out in the claims.

A structure which is a preferred embodiment of our invention is clearly illustrated 35 in the accompanying drawing forming a part of this specification in which:

Figure I is a plan view of a structure embodying the features of our invention.

Fig. II is a side elevation thereof. 40 Fig. III is a detail longitudinal section on a line corresponding to line 3—3 of Figs. I and IV.

Fig. IV is a transverse section on a line corresponding to line 4—4 of Figs. I, II 45 and III.

In the drawing similar reference characters refer to similar parts throughout the several views, and the sectional views are taken looking in the direction of the little 50 arrows at the ends of the section lines.

Referring to the drawing, 1 represents a cylinder, 2 the head thereof and 3 the piston of our improved internal combustion engine. The cylinder head is provided with a compression or combustion chamber 4 and 55 is also provided with an air inlet valve 5 and an exhaust valve 6. The exhaust valve is controlled by the rocker 7 actuated by a push rod 8. The cylinder air inlet valve 5 is controlled by the rocker member 9 actuated by the push rod 10. The means for actuating the push rods 8 and 10 are not illustrated. Various parts are shown in conventional form.

The push rod 10 is actuated to open the 65 valve 5 on the suction stroke of the piston 3. The cylinder head is provided with a bore 11 in which is a tubular member 12 extending through the chamber 4 and provided with an opening 13 therein, also with an 70 opening 14 within this chamber 4. A body member 15 is inserted in one end of the bore 11 to project into this member 12 and is provided with a fuel passage 16 communicating with the fuel feed reservoir 17. The 75 passage 16 has a nozzle 18 delivering to the charging chamber 19 within the charging chamber member 20.

This charging chamber member 20 is rotatably mounted within the tubular member 80 12 so that more or less of its ports 21 may be brought into register with the opening 13 therein, thereby varying the delivery opening between the charging chamber 19 and the cylinder chamber 4. The member 15 is 85 also provided with an exhaust passage 22 for the charging chamber, the exhaust passage registering with the hole 14 in the member 12—see Fig. III.

The charging chamber member 20 is provided with a tubular stem portion 23 having a handle 24 therein for its adjustment. A packing comprising a packing gland 25 is provided for this stem portion. The tubular stem 23 provides an air inlet passage 95 for the charging chamber, the passage being controlled by the valve 26 having a stem 27 disposed longitudinally through the tubular stem 23.

A coiled spring 28 is connected to the stem 100

- 27, the other end of the spring being connected to the lever 29 pivoted at 30 and connected by the link 31 to an arm 32 on the governor controlled rod 33. The governor 5 connections or control means for this rod are not illustrated as they form no part of our present invention.
- It will be understood that the purpose of the governor is to regulate the tension of the 10 spring and thereby vary the amount of air passing the valve 26 to vary the degree of vacuum within the charging chamber, and thereby control the amount of fuel drawn into the charging chamber.
- 15 The exhaust passage 22 is controlled by the valve 41 the stem 42 of which projects to be engaged by an arm 43 on the rock shaft 44. The rock shaft 44 is provided with a second arm 45 coating with a tappet 46 20 on the push rod 10 so that the valve 41 is opened when the air inlet valve 5 is opened. The valve actuating push rod is timed so that the valves 5 and 41 are opened on the suction stroke of the piston. However, the 25 capacity of the valve 5 is such that a vacuum is produced in the chamber 4 and through the connection to the charging chamber, a vacuum is also produced in the charging chamber. This draws the fuel through the 30 nozzle 18 into the charging chamber, the quantity of fuel delivered being governed by the degree of vacuum and this is governed by the air inlet valve 26 which is regulated by the tension of the governor control spring 35 28, as described.

On the compression stroke of the piston the air is highly compressed within the cylinder and within the charging chamber and is ignited within the charging chamber. A 40 portion of the fuel is burned within the charging chamber increasing the pressure therein and driving or ejecting the fuel now thoroughly vaporized into the cylinder through the ports 21 where the remainder 45 of the fuel mixing with the air therein burns.

The adjustment of the member 20 controls the ports 21 varying the timing of the explosions and allowing speed variation 50 without pre-ignition when running slowly.

At the end of the work stroke the exhaust valve 6 is opened so that the exhaust gases are forced out of the cylinder. This 55 exhaust stroke is followed by the suction stroke during which time the valve 41 is opened as stated so that the charging chamber is thoroughly scavenged, particularly because of the fact of air being admitted 60 through the valve 26 during this stroke.

By this arrangement, we dispense with a fuel pump, the amount of fuel delivered at each charge is regulated by air instead of by fuel valves, the fuel is drawn up by suc-

tion thereby obviating the necessity for 65 gravity flow which might flood the engine when idle, and the fuel is effectively vaporized.

We have illustrated and described our improvements in only one embodiment as 70 we believe that that will enable those skilled in the art to which my invention relates to embody or adapt the same as may be desired.

Having thus described our invention, what 75 we claim as new and desire to secure by Letters Patent is:

1. In an internal combustion engine, the combination with a cylinder, an air inlet valve and an exhaust valve therefor, of a 80 rotatably mounted charging chamber member having a peripherally disposed series of cylinder communicating ports so that the portage may be varied by the rotation of said charging chamber member, an exhaust 85 passage connecting said charging chamber to said cylinder, a valve for said exhaust passage, a fuel connection to said charging chamber, means for opening said cylinder air inlet and said exhaust passage valves 90 on the suction stroke of the engine, the capacity of the cylinder inlet valve being such that a vacuum is produced within the charging chamber and a charge of fuel is drawn into said charging chamber, an air inlet 95 valve for said charging chamber, a seating spring therefor, and means for varying the tension of said spring so that the degree of vacuum in said charging chamber is varied to regulate the fuel charge. 100

2. In an internal combustion engine, the combination with a cylinder, an air inlet valve and an exhaust valve therefor, of a rotatably mounted charging chamber member having a peripherally disposed series 105 of cylinder communicating ports so that the portage may be varied by the rotation of said charging chamber member, an exhaust passage connecting said charging chamber to said cylinder, a valve for said 110 exhaust passage, a fuel connection to said charging chamber, means for opening said cylinder air inlet and said exhaust passage valves on the suction stroke of the engine, the capacity of the cylinder inlet valve being such that a vacuum is produced within the charging chamber and a charge of fuel is drawn into said charging chamber, and an air inlet valve for said charging chamber. 115 120

3. In an internal combustion engine, the combination with a cylinder, an air inlet valve and an exhaust valve therefor, of a charging chamber communicating with said cylinder, an exhaust passage connecting said charging chamber to said cylinder, a valve for said exhaust passage, a fuel connection to said charging chamber, means for open- 125

ing said exhaust passage valve on the suction stroke of the engine, the capacity of the cylinder inlet valve being such that a vacuum is produced within the charging chamber 5 and a charge of fuel is drawn into said charging chamber, an air inlet valve for said charging chamber, a seating spring therefor, and means for varying the tension of said spring so that the degree of vacuum 10 in said charging chamber is varied to regulate the fuel charge.

4. In an internal combustion engine, the combination with a cylinder, an air inlet valve and an exhaust valve therefor, of a 15 charging chamber communicating with said cylinder, an exhaust passage connecting said charging chamber to said cylinder, a valve for said exhaust passage, a fuel connection to said charging chamber, means for opening 20 said exhaust passage valve on the suction stroke of the engine, the capacity of the cylinder inlet valve being such that a vacuum is produced within the charging chamber and a charge of fuel is drawn into 25 said charging chamber, and an air inlet valve for said charging chamber.

5. In an internal combustion engine, the combination of a cylinder, an air inlet valve therefor, a charging chamber connected to 30 deliver to said cylinder, means for varying said delivery connection, an exhaust valve connecting said charging chamber to said cylinder, a fuel feed connection to said charging chamber, means for opening said 35 cylinder air inlet and exhaust valves on the suction stroke of the engine whereby a vacuum is produced within said charging chamber and a charge of fuel is drawn into said charging chamber, a seating spring 40 therefor, and means for varying the tension of said spring thereby controlling the degree of vacuum produced in said charging chamber to regulate the fuel charge.

6. In an internal combustion engine, the 45 combination of a cylinder, an air inlet valve therefor, a charging chamber connected to deliver to said cylinder, an exhaust valve connecting said charging chamber to said cylinder, a fuel feed connection to said 50 charging chamber, means for opening said cylinder air inlet and exhaust valves on the suction stroke of the engine whereby a vacuum is produced within said charging chamber and a charge of fuel is drawn into said 55 charging chamber, an air inlet valve for said charging chamber, a seating spring therefor, and means for varying the tension of said spring thereby controlling the degree of vacuum produced in said charging 60 chamber to regulate the fuel charge.

7. In an internal combustion engine, the combination of a cylinder, an air inlet valve therefor, a charging chamber connected to deliver to said cylinder, means for varying 65 said delivery connection, an exhaust valve

connecting said charging chamber to said cylinder, a fuel feed connection to said charging chamber, means for opening said cylinder air inlet and exhaust valves on the suction stroke of the engine whereby a vacuum is produced within said charging chamber and a charge of fuel is drawn into 70 said charging chamber, and an air inlet valve for said charging chamber.

8. In an internal combustion engine, the 75 combination of a cylinder, a charging chamber connected to said cylinder by restricted and variable charge delivery openings and an exhaust connection, a fuel feed connection to said charging chamber, means for opening said exhaust connection on the suction stroke of the engine whereby a vacuum is produced within said charging chamber and a charge of fuel is drawn into the 80 charging chamber thereby, an air inlet valve 85 for said charging chamber, and means for controlling the air inlet valve whereby the amount of vacuum produced in said charging chamber is regulated for the purpose specified.

9. In an internal combustion engine, the combination of a cylinder, a charging chamber having a delivery connection and an exhaust connection to said cylinder, a fuel feed connection for said charging chamber, 95 means for opening said exhaust connection to said cylinder on the suction stroke of the engine whereby a vacuum is produced within the charging chamber to draw a charge of fuel into the same, an air inlet valve for 100 said charging chamber, and means for controlling said air inlet valve, all coacting for the purpose specified.

10. In an internal combustion engine, the combination of a cylinder, a charging chamber having a delivery connection and an exhaust connection to said cylinder, a fuel feed connection for said charging chamber, and means for opening said exhaust connection to said cylinder on the suction stroke 105 of the engine whereby a vacuum is produced within the charging chamber to draw a charge of fuel into the same, all coacting for the purpose specified.

11. In an internal combustion engine, the 115 combination of a cylinder, a charging chamber connected to deliver to said cylinder and so that on the suction stroke of the engine a vacuum is produced in said chamber, a fuel feed connection for said charging chamber 120 whereby a charge of fuel is drawn into the same by the vacuum therein, an air inlet connection for said charging chamber, means for controlling said air inlet connection and thereby varying the degree of 125 vacuum produced in said chamber by the suction stroke of the engine, and means for varying the delivery connection for said charging chamber and cylinder.

12. In an internal combustion engine, the 130

combination of a cylinder, a charging chamber connected to deliver to said cylinder and so that on the suction stroke of the engine a vacuum is produced in said chamber,
5 a fuel feed connection for said charging chamber whereby a charge of fuel is drawn into the same by the vacuum therein, an air inlet connection for said charging chamber, and means for controlling said air inlet connection and thereby varying the degree of
10

vacuum produced in said chamber by the suction stroke of the engine.

I witness whereof we have hereunto set our hands and seals in the presence of two witnesses.
